UNITED STATES PATENT OFFICE.

JOHN W. GARDNER, OF TROY, NEW YORK, ASSIGNEE TO C. W. FERGUSON COLLAR COMPANY, OF TROY, NEW YORK, A CORPORATION.

COLLAR.

1,132,254.

Specification of Letters Patent. Patented Mar. 16, 1915.

Application filed November 28, 1910. Serial No. 594,427.

To all whom it may concern:

Be it known that I, JOHN W. GARDNER, a citizen of the United States of America, residing at 383 Third avenue, in the city of 5 Troy, in the county of Rensselaer and State of New York, have invented certain new and useful Improvements in Collars, of which the following is a specification.

My invention relates to collars, and the 10 object of my invention is to provide a button-hole cover for a collar band by means of which the shirt stud shall not interfere with the cravat; together with such elements and combinations as are hereinafter more 15 particularly set forth and claimed. I accomplish these objects as shown in the accompanying drawing, in which:

Figure 1 is a plan of my button-hole cover before it is folded for use. Fig. 2 is a plan 20 of the button-hole cover with its edges turned in. Fig. 3 is a plan of the button-hole cover folded ready for attachment to the goods. Fig. 4 is an end elevation of the form shown in Fig. 3. Fig. 5 is a plan of 25 a modified form of the button-hole cover, in which a piece, S, is placed over the engaging edges of the folded strip forming the button-hole cover. Fig. 6 is an end elevation of the modified form shown in Fig. 5. Fig. 7 is a plan of a collar provided with 30 my invention before the turned-down portion is folded in position for use. Fig. 8 is a section of a collar with the turned-down portion in its position ready for use. Fig. 9 is a plan of a modified form of button hole 35 cover. Fig. 10 is a section of a collar with the turned-down portion in its position ready for use, showing the strip, W, provided with a button-hole, V, sewed to the 40 inside of the band, F.

Similar letters refer to similar parts throughout the several views.

It is of great convenience to provide on a 45 collar a means for covering the end of the stud commonly used for buttoning the collar to the shirt at the back, because otherwise it is very difficult to draw the cravat for the purpose of tying the same. It is very desirable that the covering for the 50 shirt stud should be inexpensive, easily and quickly constructed and which may be attached to the collar after the collar has been otherwise completed. It should be adapted to be strongly attached to the collar at its ends, but so arranged that it may be easily 55 separated from the collar band sufficiently to allow the insertion of the stud through the button hole beneath it. To this end I have invented a button-hole cover, which, before it is folded, in the form shown in 60 Fig. 1, has its outer edges, A, A, convex in form and has its ends slotted at B, B, so that from the medial line, C, at the end of the collar there are two outwardly extending portions, b, a, separated from each other as 65 the distance increases from said medial line.

The edges A, A, of the collar are turned over as shown at d, d, in Fig. 2. The button-hole cover is then folded along the medial line, C, and assumes the position 70 shown in Figs. 3 and 4. It is sewed through the turned-over portions and the cover is then attached to the band, F, of the collar, G, (over the button-hole, H, and adapted to be covered by the turned-down portion, J, 75 of the collar) by sewing with an overcast stitch the ends, B, B, of the button-hole cover, leaving the upper straight edge, C, and the lower convex edge, A, loose, the lower convex edge, A, preferably extending 80 below the band, F.

In the modified form shown in Figs. 5 and 6, I show the strip, E, made as the strip, A, in Fig. 1, but instead of turning down the edge, A, at d, as in Fig. 2, I place a strip, 85 S, over the edges as shown in Figs. 5 and 6, covering the raw edges of the strip, E. The strip, S, is bent at about midway between its edges at s, and its edges, t, are folded in as shown in Fig. 6, so that all the raw 90 edges of the strip, E, and the strip, S, are protected. The strip, S, is sewed to the strip, E, as shown by dotted lines, K. The form of the ends of the strips, A, and E, which when folded is such that when the 95 straight edge, C, is placed in position above the button hole in the collar band the ends flare outwardly and toward each end of the collar, is an important part of my invention; because it enables me to stitch the button-hole cover to the collar band, after the 100 collar is made, in a perfectly secure manner and without unnecessary inconvenience or the expenditure of much time, and especially because it prevents the cover from 105 shifting transversely of the collar band during laundering operation.

In Fig. 9 I show a button-hole, V, in the

strip, W. This strip, W, may be attached to the side of the band opposite to that to which the covers before mentioned are applied, in order that the shirt stud may be inserted through the button-hole, V. The arrangement of the lower edge of the strip when placed on the band so that it is convex is also an important part of my invention, as it enables the wearer to easily engage the 10 button-hole cover to pull it away from the button hole in the neck band. In practice I use two plies of cloth cut in the form shown in Fig. 1, placing one on top of the other and folding them as already described. 15 It will be seen that the edges as shown in the form illustrated in Fig. 4, as well as that illustrated in Fig. 6, are well protected from raveling or fraying. By using the overcast stitch at the ends of the button-hole cover I secure the cover in such a manner that the raw edges are covered and pro- 20

tected so that there shall be no tearing, raveling or fraying at the ends.

My invention is simple but very effective, is easily constructed and performs its functions in a highly satisfactory manner. 25

What I claim as my invention and desire to secure by Letters Patent, is:

An attachment for a collar comprising a button hole cover made up of a two ply blank having its edges convex and each end flaring, with a finishing strip covering the convex edges, said attachment secured by an overcast stitch at each end to the outer band of a collar, covering the rear button hole 30 35 therein.

In testimony whereof I have affixed my signature in presence of two witnesses.

JOHN W. GARDNER.
